UNITED STATES PATENT OFFICE

94,215

DESIGN FOR A SHOE HEEL OR SIMILAR ARTICLE

William P. Harty, Winchester, Va., assignor to
The O'Sullivan Rubber Co., Inc., Winchester,
Va., a corporation of Delaware

Application October 12, 1934, Serial No. 53,592

Term of patent 7 years

To all whom it may concern:

Be it known that I, William P. Harty, a citizen of the United States, residing in Winchester, county of Frederick, State of Virginia, have invented a new, original, and ornamental Design for a Shoe Heel or Similar Article, of which the following is a specification, reference being had to the accompanying drawing, forming a part thereof:

In the drawing:

Figure 1 is a bottom plan view of a shoe heel embodying the invention, and

Figure 2 is a section on the line 2—2 of Figure 1.

I claim:

The ornamental design for a shoe heel or similar article, as shown.

WILLIAM P. HARTY.
